METAL THREADED HANDLE

Hite Bowman Morgan, Brooklyn, N. Y.

Application July 2, 1931, Serial No. 550,805

1 Claim. (Cl. 306—30)

This invention is concerned with detachable handles and particularly with a screw type detachable handle such as is commonly used on mops, brushes and the like.

5 It has been the custom for many years to make the wooden handles for some kinds of mops and brushes with screw threads cut in the end thereof, so that they may be detachably screwed into a threaded hole in the frame of the mop or brush. 10 This construction is very advantageous because it allows the head of the mop or brush to be replaced without replacing the handle and the handles and heads may be much more conveniently packed for shipping when they are 15 separate.

There are, however, several very marked disadvantages to this construction. In the first place, the handles are ordinarily made of wood and wood is not well adapted to machining such 20 as threading, and is likely to be broken or macerated if considerable care is not taken in the cutting of the threads. Another difficulty is encountered in keeping the handle tightly screwed into the brush or mop when the device is in use, 25 for, as the wood dries out or becomes wet it tends to shrink or expand or warp or crack, and all of these changes eventually tend to loosen the handle in the mop. A still further difficulty is experienced by practically all users of this kind 30 of mops and brushes on account of the stripping or breaking off of the threads on the handle or in the frame. Wood has little strength across the grain and as the threads are customarily cut the grain runs transverse to the threads and all of 35 the strain on the threads is cross-grain to the wood.

In order to eliminate these difficulties, this apparently simple structure has recently become the subject of considerable study and efforts have 40 been repeatedly made to improve it. It has been proposed to cover the threads on the handle with a metal covering and this has been done and some of the difficulties have thereby been overcome, because the metal covering covers slight flaws in 45 the wood caused by machining and because it strengthens the threads.

The major difficulty, however, is that the handle becomes loose in the frame and that while the brush or mop is being used, the head suddenly 50 loosens on the handle or drops off. This is a most aggravating occurrence, especially if it recurs frequently and even the mops and brushes having metal covered handles are not free from it. Furthermore, the metal covered handles are 55 subject to the difficulty that the covering itself

must be anchored to the handle and this usually involves a comparatively expensive and tedious process of nailing or tacking the covering in place. The heads of the nails or tacks are then a source of trouble as if they are not properly 60 pounded down they furnish projections which are likely to catch on draperies, rugs, clothes and the like and cause damage.

The object of this invention is to provide a 65 mop or brush handle of this screw type which will be free from the tendency to come loose on the handle, in which the threads on the handle are protected by a metal cover and yet which has no projections which are likely to catch on fabrics and the like, and which may be cheaply 70 manufactured, without the use of tacks or nails.

This invention specifically comprises a wooden 75 mop handle with threads cut in one end and a metal cover screwed over the threads, which cover conforms closely to the shape of the handle and extends a short distance above the threads. The handle is formed above the threads with an outwardly tapering portion which may have either a straight taper or a convex taper, preferably the latter. A series of projections are 80 punched inwardly from the metal cover into the handle to hold the cover in place on the handle. The threads are preferably tapered so that they decrease in size toward the end of the handle.

In the usual type of handle there is a definite 85 shoulder above the threads, which contacts flatly with the frame and provides a stop for the handle when it is screwed in place. The difficulty with this is that if the handle is even very 90 slightly moved the shoulder is out of engagement and the handle is loose and free to unscrew.

By shaping the handle so that it has a straight 95 or convex taper at the end of the threads, a wedging action between the frame and the handle above the threads is caused when the handle is screwed in place which prevents the handle from unscrewing as it will do with a straight shoulder or a concave taper.

The projections which hold the metal cover 100 in place may easily be made by a punch which simply strikes them inwardly after the cover is in place on the handles. There are no nails or tacks needed, and no chance of any outwardly 105 extending burrs or nail heads to catch on fabrics and the like.

For a more detailed description of this invention reference may be had to the accompanying drawing, in which

Fig. 1 is a sectional elevation view;

Fig. 2 is an elevation showing the projections which hold the cover in place in the preferred form of device;

5 Fig. 3 is a sectional plan view taken on line 3-3 of Fig. 2;

Fig. 4 is an elevation view showing the cover held in place by a pin.

10 Fig. 5 is a sectional elevation of the device in which the taper at the end of the threads is straight instead of convex.

15 As shown in the drawing, the handle is composed of an elongated cylindrical rod 10, of wood or similar material and has one end machined to form threads 11 and a tapered shoulder 12 of convex shape at the upper end of the threads.

20 A metal cover 13 of the same shape is slipped over the threads and shoulder and is preferably held in place by projections 14 struck inwardly from the cover 13. These projections have the form of small pointed tongues and extend inwardly at an angle and are pointed in the direction in which the cover would unscrew off of the handle thus locking the cover against such movement.

25 The frame 15 of the brush or whatever other implement is to be used with this handle has an opening 16 therein to receive the end of the handle and this opening may be lined with metal sheet 17 if desired. When the handle is screwed

30

down into the frame the tapered shoulder 12 wedges into the opening and securely locks the handle against any wobbling or rotating. Thus the handle is firmly secured to the brush until such a time as it is purposely detached by forcibly twisting the handle in the frame.

80

In Fig. 3 a cross section of the handle is shown which clearly illustrates the locking action of the inwardly projecting lugs in holding the cover in place upon the handle.

85

A slight modification of the manner of securing the cover placed upon the handle is shown in Fig. 4 in which the cover is secured on the handle by a pin 18 passing through the upper end of the cover and into the handle.

90

Another modification of the structure of this invention is shown in Fig. 5 in which there is formed at the upper end of the threads a straight taper 20 instead of the convex taper 12.

95

I claim:

A handle having a threaded end portion of reduced diameter, and a metal cover secured on the end of the handle, said cover having a threaded outer end portion conforming to the reduced end of the handle and a smooth inner end portion tapering outwardly from the threaded portion, the said inner end portion serving to wedge the handle in the socket into which it is screwed.
